FIREARM

Newton S. Hillyard, St. Joseph, Mo.

Application April 12, 1935, Serial No. 15,961

7 Claims.

(Cl. 42—59)

This invention relates to firearms, particularly to those of that character for use in firing gas producing shells and has for its principal objects to provide a firearm of this type that is automatic in operation and capable of successively firing a plurality of shells with one loading.

10 Other important objects of the invention are to provide a well balanced, simple and compact construction that is convenient to carry and conceal, to provide for fast, positive firing action with a minimum recoil, to facilitate reloading after the shells have been fired, and to generally increase the effectiveness of this type of firearm.

15 It is a further object of the invention to provide a firearm with a trigger extending the full length of the hand grip to obviate the hazard of having it jerked or twisted from the hand when dealing with a mob.

20 In accomplishing these and other objects of the invention, as hereinafter pointed out, I have provided improved details of structure, the pre-

ferred form of which is illustrated in the accompanying drawings, wherein:

25 Fig. 1 is a perspective view of a firearm for discharging gas producing shells and embodying the features of the present invention.

Fig. 2 is a similar perspective view with the cover section of the frame removed to better illustrate the actuating mechanism for effecting firing of the shells and for successively moving the shells into firing position.

Fig. 3 shows the shell cylinder removed from the frame for discharging the empty shells prior to reloading.

Fig. 4 is a similar view showing the cylinder reloaded and ready to be replaced on the frame.

Fig. 5 is a section through the shell cylinder on the line 5-5, Fig. 9, particularly illustrating the cylinder catch and release mechanism, the catch being shown in released position, and the cylinder partly withdrawn from its spindle.

Fig. 6 is a longitudinal central section through the firearm, a part of the ratchet lever being broken away to better illustrate the sear actuating lever.

Fig. 7 is a similar view showing the hammer being moved to cocked position and the shell cylinder being rotated to bring a shell in line with the firing pin.

Fig. 8 is a similar view after the hammer has been cocked and is being released by the sear.

Fig. 9 is a cross section through the cylinder on the line 9—9, Fig. 6.

55 Fig. 10 is a view of the breech end of the

cylinder particularly illustrating the ratchet grooves and the notches for latching the cylinder in firing position.

Fig. 11 is a fragmentary section through the frame on the line ||—|| Fig. 6.

Fig. 12 is a horizontal section on the line 12—12, Fig. 7.

Fig. 13 is a detail perspective view of the ratchet lever.

Referring more in detail to the drawings: 10
1 designates a firearm including a frame 2 comprising mounting and cover sections 3 and 4 that are preferably formed of thin metal shaped to provide hollow handle grip and head portions 5 and 6 to house the actuating mechanisms, the sections being secured together by screws 7 extending through the handle portions 5 and by screws 8 that extend through a circular base plate 9 of the mounting section and into threaded sockets 10 that are provided in the forward edge of the cover section. The sections 3 and 4 are of substantially identical shape except for the base plate 9 which forms an abutment for the cylinder 11 later described. The cylinder is rotatably mounted on a spindle 12 25 comprising a rod having a cylindrical bearing portion 13 provided with a reduced threaded shank 14 on the end thereof that is threaded into an internally threaded socket 15 provided in the axis of the circular base 9, the shoulder formed by the reduced shank 14 engaging against the outer face of the circular base to wedge the threads of the shank in the socket and thereby preventing unthreading thereof. 30

The shell cylinder includes a body portion 17 having a circular base flange 18 conforming in diameter to the circular base 9 of the frame and which rotates on the spindle in face to face engagement therewith as illustrated in Figs. 1 and 2. 40

Formed in the body portion 17 of the cylinder circumferentially of an axial bore 19 that accommodates the spindle is a circular series of shell chambers 20 of suitable diameter to receive gas shells 21 of standard gauge. The breech ends 45 of the chambers are counter-bored as at 22 to accommodate the rims 23 of the shells to retain the shells against axial movement in the cylinder when the cylinder is in contact with the base plate. In order to lighten the body portion of 50 the cylinder, the outer periphery thereof conforms in shape to the shell chambers as best illustrated in Fig. 9.

The bore 19 extends entirely through the cylinder and is counter-bored between the ends 55.

thereof as at 24 to provide bearing portions 25 and 26 conforming in diameter to the spindle. The inner end of the counter-bore adjacent the bearing portion 26 forms an annular shoulder 27 adapted to be engaged by a catch 28 to rotatably retain the cylinder on the spindle.

The catch 28 is pivotally mounted in a radial recess 30 formed in the side of the spindle as best illustrated in Fig. 6, the catch being pivotally mounted on a pin 31 extending diametrically through the spindle and through an ear 32 on the catch. The rear end of the catch includes a latch portion 33 adapted to engage against the shoulder 27 and a tail portion 34 that engages against the inner periphery of the bearing portion 26 to normally retain a hook 35 on the forward end of the latch in engagement with a catch release 36.

The catch release 36 includes a shank portion 37 reciprocably mounted in an axial bore extending inwardly from the outer end of the spindle and has a V-shaped notch 38 in its inner end to form an inclined portion 39 and a shoulder 40 to respectively engage complementary cam and shoulder portions 41 and 42 on the hook shaped end of the latch.

Provided on the outer end of the rod 37 is a cylindrical button 43 that is normally spaced from the end of the spindle as at 44 and normally projects from the bore of the cylinder so that the head may be moved into the open end of the bore to cause the cam shaped face 39 on the rod to cam the hook shaped end of the catch outwardly and effect release of the shoulder 33 from engagement with the annular shoulder 27 against action of a spring 45 that yieldingly retains the tail portion 34 and shoulder 33 in engagement with the cylinder.

It is apparent that when the cylinder is sleeved over the spindle, the bearing portion 26 will engage the latch to cause the latch to move into the recess 30 compressing the spring 45; but as soon as the shoulder 33 passes off the shoulder bearing portion 26, the spring will move the catch into engaging position with the annular shoulder 27 to prevent retraction of the cylinder. The cylinder, however, is freely rotatable on the spindle due to the counter-bore 24 which accommodates the projecting portions of the catch and the annular shoulder forms a stop for the catch in any position of the cylinder.

It is also apparent that the hook shaped end of the latch being in hooked engagement with the catch release retains the release in functional position within the bore of the spindle.

When the cylinder is to be removed, the button 43 of the latch is pressed into the bearing portion 25 to cause the rod to cam the latch into released position as above described, whereupon the cylinder may be readily withdrawn from the spindle.

Located in the head of the mounting section of the frame and in axial alignment with the circular path of travel of the shell chamber axis is a hammer housing 46 that is preferably formed integrally therewith and has an inner cylindrical bore 47 opening from the forward end thereof but terminating short of its opposite end to provide a spring seat 48. Reciprocable in the hammer housing is a hammer 49 including a cylindrical body having an annular V-shaped groove 51 thereon to form a sear engaging shoulder 52 that is adapted to be engaged by a sear 53 which engages and moves the hammer to cocked position as later described.

Formed on the forward end of the cylindrical body of the hammer, in the axis thereof, is a firing pin 54 adapted to project through an opening 55 in the circular base plate 9 to engage the priming cup 56 of one of the gas producing shells 21 and located on the opposite end of the cylindrical body is a boss 57 forming a shoulder 58 therewith to seat the end of a coiled hammer spring 59 having its opposite end engaging against the seat 48 previously mentioned.

The spring 59 normally retains the hammer in projected position and means must be provided for yieldingly opposing it so as to prevent the firing pin from dragging against the shells at the time the cylinder is rotated. This is accomplished by means of a coil spring 60 sleeved over the firing pin and having one end anchored in the bottom of the circular groove that is formed in the body portion of the hammer about the periphery of the firing pin as best illustrated in Fig. 6.

When the hammer spring 59 is relaxed, the spring 60 preponderates thereover to yieldingly retain the firing pin from engagement with the shell; however, during release of the hammer, momentum imparted to the hammer by the hammer spring 59 effects compression of the spring 60 so that the firing pin is driven into firing engagement with the shell. After the energy of the spring 59 is expended, the spring 60 comes into play to move the firing pin away from the shell to permit rotation of the cylinder.

In order to stop the cylinder so that one of the shell chambers 20 is always aligned with the firing pin, I provide a cylinder stop 61 that is pivotally mounted on a pin 62 extending across a notch 63 that is formed in the periphery of the circular base at a point diametrically opposed to the position of the firing pin as best illustrated in Figs. 6 to 8, inclusive.

The stop 61 includes a lever having one end 64 operable in the slot 63 and provided with a detent 65 for engaging one of a plurality of radial notches 66 formed in the face of the base flange 18 as best illustrated in Fig. 10, there being one notch for each shell chamber. The detent portion of the stop lever is normally urged to notch engaging position under action of a spring 67 that is mounted in a recess in the circular base and which engages the opposite end of a stop lever.

Thus, when the detent portion of the stop lever is engaged with one of the notches 66, the cylinder is held from rotation in either direction so that the chamber opposite the notch is retained in firing position relatively to the firing pin.

Extending from the lower end of the handle grip portion of the base section is an ear 69 carrying a pin 70 that cooperates with a similar pin 71 extending across the frame sections at a point adjacent the stop lever 61 to mount a trigger including a bar 72 and a pivotally connected trigger lever 73 that is connected therewith by a pin 74 extending through the upper end of the bar and through the depending arm 75 of the trigger lever, the trigger lever being pivoted on the pin 71 and the slotted lower end of the bar on the pin 70.

It is thus apparent that the trigger bar extends substantially the full length of the handle grip so that it may be engaged by all of the fingers of the hand when the gun is held in firing position.

Upon contracting the fingers about the grip, the trigger bar will be caused to pivot on the pin 70 and the trigger lever on the pin 71 to successively effect actuation of the cylinder stop lever 61, a sear supporting lever 76 and a ratchet lever 77 to successively effect release of the cylinder, initial cocking movement of the hammer and intermittent rotation of the cylinder to bring a shell into firing position with the firing pin as now to be described.

Pivotedly mounted on a screw 7 that extends through the head of the frame and located between bosses 78 projecting inwardly from the sides of the frame sections is the sear supporting lever 76 which is in the form of a bell crank lever including a forwardly extending arm 79 having a rounded end 80 thereon adapted to engage a rounded cam face 81 on the spring pressed end of the stop lever. The other arm 82 of the sear lever extends upwardly in the direction of the hammer and has a yoke shaped head 83 in which is pivotally mounted the end of the sear 53, the sear being pivotally mounted in the yoke on a pin 84 as best illustrated in Fig. 2. The opposite end of the sear extends across the yoke and has a hook shaped end 85 extending through an elongated slot 86 in the hammer housing to engage the shoulder 52, the sear being urged to shoulder engaging position by means of a plunger 87 that is slidable in a bore 88 formed in the yoke shaped head under response of a coil spring 89 seated in the bore and having an end engaging against the inner end of the plunger to cause the plunger to move the sear in a clock-wise direction as shown in Figs. 6 to 8, inclusive.

Extending laterally from the trigger lever is an arm 90 having its free end connected by links 91 and 92 with the forwardly extending arm 79 of the sear supporting lever, the lower end of the links being pivotally connected to the ends of a pin 93 carried by the end of the arm 90 and the upper end of the links being connected by a pin 94 that is carried in an ear 95 formed as a part of the lever arm 79.

In order to restore the trigger mechanism to normal position after each trip of the trigger, the pin 93 carries a depending link 96 to which is connected one end of a coil spring 97 having its opposite end 98 anchored to a pin 99 that is carried by the mounting section of the frame as best illustrated in Fig. 2.

With the construction thus far described, actuation of the trigger lever will cause the sear lever to rock in a clock-wise direction, Fig. 6, so that the rounded end 80 thereof engages the cammed end of the cylinder stop lever to effect release of the detent 65 from engagement with one of the notches 66. Simultaneously, the other arm of the sear supporting lever swings retractively to retract the hammer 49 compressing the spring 59.

Simultaneously with movement of the hammer, and after the catch has been released, the ratchet lever 77 is operated to effect rotation of the shell cylinder to bring a loaded shell into alignment with the firing pin as now to be described.

The ratchet lever is best illustrated in Fig. 13 and is shown as including a plate 100 having a bearing hub 101 that is pivotally mounted on a pin 102 carried by the mounting section of the frame at a point below the hammer housing. The opposite end of the plate 100 projects forwardly and downwardly alongside the cylinder

stop lever and extends through an elongated slot 103 extending parallel with and offset laterally from the notch 63 which forms a guide to retain the lever for movement in a fixed arcuate path to carry a click 104 into propelling engagement with the ratchet grooves of a cylinder. The click 104 is pivotally mounted on a pin 105 that is carried by the end of the plate 100 and has a tooth 106 that is urged into engagement with the inner face of the cylinder flange by a spring 107 having one end 108 engaging the click and its opposite end formed in a coil and fixed to the end of the ratchet lever as indicated at 109.

Upon initial movement of the ratchet lever, the click engages in one of the radial notches 110 to rotate the cylinder sufficiently to carry one of the shell chambers into firing position.

In order to provide lag between the movement of the ratchet lever and the pin 94 to allow time for releasing the cylinder stop, the pin extends through an enlarged notch 111 that is formed in the arm 100 between the body portion thereof and an extending finger 112, as best shown in Fig. 13 so that when the trigger lever is moving the sear lever to effect release of the cylinder stop, the pin 94 is moving through the notch 111.

By the time the rounded end of the sear lever has ridden off the cam shaped end of the stop lever, the pin 94 engages under the body portion of the ratchet lever to raise the lever and effect rotation of the cylinder.

As soon as the stop lever has been lifted out of the notch 66, the detent 65 will drag over the face of the base flange until the succeeding notch 66 is brought into alignment therewith. The spring 67, acting against the stop lever, will then cause the detent to drop into the notch to hold the cylinder in advanced position.

Due to the fact that the hammer has not completed its cocking stroke at the time the cylinder has come to rest, the upper movement of the ratchet lever is continued through continued movement of the sear lever. Therefore, the base flange of the cylinder is provided with grooves 113 connected with the ends of the ratchet notches 110 and extending in parallel relation with the radial diameter of the shell chambers. The length of the ratchet notches 110 being such that as soon as the detent is engaged to stop rotation of the cylinder, the tooth 106 of the click will have ridden out of the notch and into the groove 113 where it is free to move to allow final movement of the hammer.

When the hammer has reached the end of its stroke, or cocked position, the sear 53 is automatically released from engagement therewith due to the fact that the upper edge 53' thereof is brought into camming engagement with the end 114 of the slot 71 which causes the sear to be cammed downwardly and outwardly away from the annular shoulder 52 of the hammer as illustrated in Fig. 8.

The stored up tension of the spring 59 then comes into play to drive the hammer in the opposite direction to cause the firing pin to explode the shell.

As above pointed out, the stored up tension of the spring and momentum of the hammer 70 causes initial compression of the spring 69, but as soon as the shell has been fired and the force of the spring 59 expended, the spring 69 comes into play to space the end of the firing pin from the discharged shell. Upon release of the trig-

ger bar, the spring 97 restores the parts to normal position.

The firing action can then be repeated by again gripping the trigger bar to effect release 5 of and rotation of the cylinder to bring the succeeding shell into firing position. Simultaneously, the hammer will be cocked and released to fire the shell in the same manner as above pointed out. The firing can continue until all 10 the shells have been fired simply by releasing and again gripping the trigger after each firing operation.

In loading a firearm constructed and assembled as described, the catch release button 43 15 is pressed into the bearing opening 25 to cause release of the cylinder catch 28. The cylinder is then free to be withdrawn from the spindle as shown in Fig. 5.

The shells 20 may then be inserted through 20 the breech ends of the chambers so that the rims thereof are seated in the counter-bores 22.

The cylinder is then reapplied to the spindle and as soon as the shoulder portion of the cylinder catch lever overrides the annular shoulder 25 27, the catch will be automatically moved to latched position by the spring 45 which also returns the release button 43 to its normal position.

When the gun is to be used, it is held in the 30 hand in such a manner that the fingers extend about the trigger bar and the cylinder is pointed in the direction at which the gas is to be discharged. Then, by contracting the fingers about the grip on the firearm, the trigger lever will 35 be actuated to first effect release of the cylinder stop, and initial retractive movement of the hammer. Then the ratchet lever will come into play to cause rotation of the cylinder to move the shell, which is then in firing position, 40 away from the firing pin and the succeeding shell into firing position.

As soon as one of the notches 66 has been moved into alignment with the stop lever, the 45 spring of the stop lever will move it into engagement therewith to stop rotation of the cylinder. Continued pressure applied to the trigger bar will complete movement to cause final 50 cocking movement of the hammer and automatic release thereof to fire the shell. The firearm can be immediately refired upon allowing the spring to return the trigger bar and then regripping the trigger bar to repeat the operations above described.

The device may be successively fired in like 55 manner until all of the shells have been discharged. Then, the cylinder may be readily removed by pressing on the button 43 and withdrawing the cylinder from the spindle with one hand while the frame of the gun is held in 60 the other hand as shown in Fig. 3.

Upon inverting the cylinder, the discharged 65 shells will fall from the chamber as shown, after which new shells can be quickly inserted into the shell chambers and the cylinder reapplied to the spindle.

From the foregoing it is apparent that I have provided a firearm for discharging gas shells in a most expeditious manner and that a plurality of shells may be fired successively within 70 the loading capacity of the cylinder.

It is also obvious that the device is of simple, compact and balanced construction so that it is convenient to carry and conceal. After firing, the empty shells are quickly removed 75 and new shells inserted so that the device can

be replaced in operation with a minimum amount of delay.

A device constructed as described has a moral effect far greater than single shot weapons and is far more effective in subduing individuals or dispersing mobs. 5

It is also apparent that due to the fact of the full trigger grip, the hazard of having the weapon jerked or twisted from the hand is reduced to a minimum and a far more accurate aim is assured due to the uniform pull of the trigger. 10

What I claim and desire to secure by Letters Patent is:

1. In a device of the character described, a 15 frame, a cylinder rotatably mounted on the frame and provided with a plurality of shell chambers arranged in series about the axis of the cylinder and having ratchet guide portions corresponding to spacing of the respective chambers, shell firing means on the frame, a stop latch for normally locking the cylinder from rotation, means for releasing said stop latch, a ratchet lever for rotating the cylinder to successively present the shell chambers into registry 20 with the firing means and having a portion movable in said guide portions for retaining the cylinder with one of the shell chambers in registry with the firing means, and a lost motion connection between the ratchet lever and said 25 releasing means whereby the ratchet lever is operated by the releasing means.

2. In a device of the character described, a 30 frame, a cylinder rotatably mounted on the frame and provided with a plurality of shell 35 chambers arranged in series about the axis of said cylinder and having ratchet engaging shoulders terminating in guide portions corresponding to spacing of the respective shell chambers, firing means on the frame, a stop latch 40 normally retaining the cylinder from rotation, means for releasing the stop latch including means for actuating the firing means, and a ratchet lever having lost motion connection with said release means for engaging said shoulders 45 and movable in said guide portions for retaining the cylinder with one of the shell chambers in registry with the firing means during final operation of said releasing means.

3. In a device of the character described, a 50 frame, a spindle projecting from the frame, a cylinder rotatably mounted on the spindle and provided with a plurality of shell chambers arranged in series about said spindle and having ratchet engaging shoulders terminating in guide 55 portions corresponding to spacing of the respective shell chambers, firing means on the frame, a stop latch normally retaining the cylinder from rotation, a bell crank having one arm for releasing the stop latch and its other arm connected with the firing means, a ratchet lever having lost motion connection with the bell crank, a click on said lever for engaging said shoulders and movable in said guide portions for retaining the cylinder with one of the shell chambers in registry with the firing means, a second bell 60 crank having one arm connected with the first bell crank, and a grip bar having one end connected with the other arm of the last named bell crank and its other end pivoted to said frame. 65

4. A device of the character described including a frame, a cylinder having a plurality of shell chambers arranged in circular series about the axis of the cylinder, means for rotatably 70

mounting the cylinder on the frame, shell firing means on the frame, means for actuating said shell firing means including cylinder rotating means, means having lost motion connection with said shell firing means for effecting lag between actuation of the shell firing means and rotation of said cylinder, a trigger comprising a bar having one end pivoted to the lower end of said frame, and a bell crank having one arm connected with the shell firing means and an arm pivotally connected with the upper end of said bar.

5. A device of the character described including a frame, a cylinder having a plurality of shell chambers arranged in circular series about the axis of the cylinder, means for rotatably mounting the cylinder on the frame, shell firing means on the frame, a stop lever for normally retaining the cylinder against rotation relatively to the frame, a ratchet lever pivoted on the frame and having a click engaging the cylinder to effect rotation thereof, a bell crank lever pivoted on the frame having a cam portion for engaging said stop lever to release the cylinder, 25 means connecting the bell crank lever with the ratchet lever, a sear carried by the bell crank lever and engageable with the shell firing means, and a trigger bar having one end pivoted to said frame and its other end connected with the bell crank lever for rocking the bell crank lever to effect actuation of the shell firing means.

6. A device of the character described includ-

ing a housing comprising mounting and cover sections having hand grip portions, a cylinder having a plurality of shell chambers arranged in circular series about the axis of the cylinder, means for rotatably mounting the cylinder on one of the sections, shell firing means enclosed by said sections, means in said sections for rotating the cylinder to successively advance the shell chambers to the firing means, and a trigger bar pivoted to the upper and lower ends of said hand grip portions having connection with said cylinder rotating means and including means for actuating said firing means.

7. A device of the character described including a housing comprising mounting and cover sections having hand grip portions, a cylinder having a series of shell chambers arranged in circular series about a bearing opening in the axis of the cylinder, a spindle fixed to one of the sections extending through said bearing opening for rotatably mounting the cylinder, means housed in the spindle for releasably latching the cylinder on the spindle, means in the sections for rotating the cylinder, means for latching the cylinder in selected position relatively to the housing, shell firing means in the sections, and a trigger bar pivotally connected with the upper and lower ends of said hand grip portions for releasing said latching means and actuating said rotating means including means for operating the shell firing means.

NEWTON S. HILLYARD.
